UNITED STATES PATENT OFFICE

RAYNARD CHRISTIANSON, OF PITTSBURGH, PENNSYLVANIA, ASSIGNOR TO THE KOPERS COMPANY, A CORPORATION OF DELAWARE

COKE-OVEN-DOOR MACHINE

Application filed December 5, 1927. Serial No. 237,605.

My invention relates to door machines for coke ovens and particularly to machines for manipulating the doors of the coke side of a battery of horizontal coking retort ovens.

5 An object of my invention is to provide a simple and efficient mechanism for removing doors from coke ovens and actuating them to such position that the machine and the door that has been removed may be easily moved

10 out of alinement with the corresponding oven.

A further object of my invention is to provide a mechanism for removing doors from coke ovens and manipulating them within the relatively small clearances by which such

15 operations are ordinarily limited.

A further object of my invention is to provide a mechanism for removing and replacing coke-oven doors that shall remove the door to a relatively remote position from the oven 20 and at the same time retain the mechanism substantially within the limits of the door machine.

A still further object of my invention is to provide a door machine which places the coke 25 oven doors in convenient position for cleaning and which furnishes a substantially unobstructed passageway therethrough for an operator.

Door machines of the prior art have operated 30 in several ways to remove coke-oven doors from the coke side of a coke-oven battery. In certain of these machines, the movable mechanism for controlling the coke-oven doors has reciprocated in alinement 35 with the oven and transversely to the door machine to remove or to replace the doors. Such operation is inconvenient and undesirable by reason of the necessary length of the mechanism and the fact that it may project 40 beyond the frame of the door machine in which case it may strike other objects or apparatus during the movement of the door machine along the side of the battery. Other door machines have operated to swing the

45 door through a vertical arc in order to avoid the reciprocating mechanism referred to above. Such operation is attended with considerable difficulty and the mechanism for controlling the doors is complicated and expensive.

Numerous other arrangements have been proposed but substantially all of them operate with one or more of the disadvantages referred to above and it is an object of the present invention to provide a machine in 55 which these constructional difficulties and operating inconveniences are entirely avoided.

In accordance with the present invention, I provide a door machine in which, by means of a simple mechanism, the door to be removed is first unlatched and is then withdrawn in a path that comprises a relatively short straight line and a curved path in which the door is swung horizontally through an angle of approximately 90°. The carriage or the mechanism for manipulating the door is also turned through an angle of 90°, whereby it is actuated from a position transverse to the door machine to one in alinement therewith whereby the door carriage is 70 substantially entirely within the limits of the door machine.

In general, the mechanism by means of which the doors are controlled comprises two door-supporting hooks that extend from 75 the carriage and which may be operated to unlatch the door. The carriage is mounted to somewhat overhang the main body portion of the door machine by two horizontal links of different lengths. When the carriage is 80 caused to move to withdraw the door, it first moves in a comparatively straight line, whereupon the difference in length of the pivotally connected links causes it to be swung through a curved path and to assume 85 a position substantially in alinement with the door machine and within the limits of the frame of the latter. The machine may then be moved out of alinement with the coke oven from which the door has been 90 removed without danger that the carriage or the door will strike any projecting apparatus along the side of the battery.

The details of my invention will be described in connection with the accompanying 95 drawings, in which

Figure 1 is a view in transverse vertical section of a battery of horizontal coking retort ovens and associated apparatus including the door machine of my invention; 100

Fig. 2 is a top plan view of the door machine, parts being broken away, a portion of a coke oven being shown in section;

Fig. 3 is a view in side elevation of the door machine of Fig. 2;

Fig. 4 is a view in end elevation of the door machine of Fig. 2, parts being broken away, a portion of a coke oven being shown in outline; and

Fig. 5 is an enlarged sectional view taken on line V—V of Fig. 4.

Referring particularly to Fig. 1, a battery of horizontal coke ovens comprises a series of coke ovens 2, only one of which appears in the drawing. Each of the ovens is provided with the usual top 3, floors 4 and removable doors 5 and 6 that are located, respectively, on the pusher side and the coke side of the battery. Each oven is further provided with an ascension pipe 7 that is connected to a collecting main 8.

A larry car 9 of usual construction supplies coal for charging the ovens through the charging holes 10. The battery is also provided with the usual regenerators 12, producer gas mains 13, coal gas mains 14 and waste gas mains 15. A quenching car 16, which operates along the side of the battery, receives the hot coke after it has been discharged therefrom by means of the pusher ram 17 that is located on the usual pusher machine 18. A door machine 19, which constitutes the subject-matter of the present invention, operates on rails 20 along the coke side of the battery and is provided for the purpose of manipulating the doors 6.

Reference may now be had to Figs. 2, 3, 4 and 5, in which the details of the door machine 19 are illustrated. The door machine 19 comprises a main body portion having the form of a structural framework 21 that is mounted on wheels 22 for operation on the track 20. The door machine 19 is moved along the track 20 by means of an electric motor 23 that is suitably geared to the driving wheels of the door machine and that is provided with a controller 24. A movable carriage 25 is mounted upon and supported from the forward end of the door machine 50 by means of two pivotally-mounted bifurcated arms or links 26 and 27. The links 26 and 27, which are pivotally connected to the carriage at spaced points, are also pivotally connected to the main body portion of the door machine for pivotal movement. The link 26 is materially longer than the link 27 whereby endwise movement of the carriage will cause it to change its alinement.

The inner end of the link 27 is rigidly connected to a bevel gear 28 that is rotatably mounted on a shaft 29 and is operatively connected through a train of gear mechanism 30 to an electric motor 31. The link 26 is freely movable at its respective pivotal connections.

The carriage 25, which corresponds to the usual mechanism known as a door extractor, has a vertically-extending portion 33, to which the bifurcated links 26 and 27 are secured and which also supports two horizontal arms 34 and 35 that are provided with hooks for engaging the frames of the doors 6. The arms 34 and 35, which are connected by a rod 36 for simultaneous movement, are pivotally mounted at 37 and 38, respectively. The arm 34 is provided with a crank arm 39, by means of which the arms 34 and 35 are operated through a mechanism comprising a screw-threaded shaft 40, a nut 41 having a gear 42 that is connected through suitable gear mechanism to an electric motor 43. This mechanism, which is usual with door extractors, raises and lowers the arms 34 and 35 upon operation of the motor 43 in the corresponding direction, the nut 41, which cannot move axially, causing the shaft 40 to be reciprocated correspondingly, as will be readily understood.

It may be assumed that it is desired to remove the door 6 of the oven 2 of Fig. 1 and that the door machine 19 has been actuated to such position that the carriage 25 and its connected parts are in alinement with the door to be removed. The carriage 25 and its connected parts, including the arms 34 and 35, are caused to move toward the door 6 by operation of the motor 31 through its controller 45 that is located for convenient operation by the operator. The motor 43 is then operated by means of its controller 46 to raise the arms 34 and 35, whereupon the usual latches 47 are lifted from engagement with angle irons on the buckstays 48 and the hook portions of the arms engage the projections 49 on the door. The motor 43 will stall before the arms assume the entire weight of the door, thereby precluding lifting of the door which is undesirable.

Under these conditions, the arms 34 and 35 do not lift the door but are in position to support its weight when it is withdrawn from the oven, the sill of the door frame being slightly inclined downwardly to provide clearance at the bottom of the door. The motor 31 is now energized to operate through the gear mechanism comprising the bevel gear 28 to rotate the link 27 about the shaft 29 to withdraw the carriage 25 and the door 6 substantially horizontally along the lines represented by the curves 50 and 51 in Fig. 2. It will be noted that the movement of the door is through a horizontal path that is at first approximately a straight line and it is then caused to swing through an angle of substantially 90° to the position indicated by dotted lines. The carriage 25 occupies a corresponding position in approximately the center of the door machine and with only a small portion projecting beyond the front of the latter.

5 The door machine 19, together with the door 6 that has been removed, is then actuated along the track 20 out of alinement with the oven in order that the coke may be discharged therefrom. In case the coke guide is attached to the door machine, the latter will be moved in a forward direction to such position that the coke guide is in alinement with the oven.

10 The position of the door on the machine with its inner side presented outwardly is such that the inner surfaces are accessible for cleaning or inspection. This condition is not only a decided advantage with ordinary doors, but is practically a necessity when self-sealing doors as at present constructed are used as the sealing means, such as asbestos ropes, must be free to seat firmly on the flanges of the end frames of the ovens. The 15 frames of the doors must, therefore, be free from pitch, or other adherent material which might prevent gas-tight sealing of the doors.

20 When it is desired to replace the door 6 in operative position, the operation described above occurs in reverse order. The door machine is moved along the track 20 to the position in which it is illustrated in Fig. 2. The motor 31 is then operated to cause the carriage 25 with the door 6 to move horizontally from the dotted-line position along the curves 50 and 51 until the door has been inserted in the end of the oven. The motor 43 is then operated to lower the arms 34 and 35 to permit the door to be latched in position.

25 It will be noted that the door machine of my invention operates to withdraw and to replace coke-oven doors through a path that insures that the door has the proper movement with respect to the framework at the end of the oven during the initial portion of its withdrawal and that it is thereafter operated through such angle as will insure that its stationary position upon the door machine is one wherein it will be out of alinement with any obstruction or projecting apparatus of the coke oven. The straight-line portion of the horizontal path of movement also insures that the doors may be inserted 30 easily and conveniently to their operative positions. In case self-sealing doors are used, this path of movement is essential to the operation of the door without damage to the sealing means.

35 The position of the mechanism is at all times such that a passageway through the machine is provided for an operator. The door is accessible for inspection and cleaning.

40 The foregoing and other advantages will be apparent to those skilled in the art of operating coke ovens.

I claim as my invention:

45 1. Coke-oven apparatus comprising a removable coke-oven door and a door machine

for removing said door, said door machine having means for successively unlatching said door, withdrawing it in substantially a straight line and swinging it through an angle of substantially 90°, said means comprising a door-engaging mechanism, spaced members of unequal length for pivotally supporting said mechanism and actuating means for said mechanism whereby the latter, upon movement upon its supports, is withdrawn and swung as aforesaid.

2. Coke-oven apparatus comprising a removable coke-oven door and a door machine for removing said door, said door machine having a mechanism for unlatching and supporting said door and means comprising a carriage and two spaced arms of unequal length for pivotally supporting said carriage for successively withdrawing said mechanism in a substantially straight line and then swinging it through an angle of substantially 90°.

3. Coke-oven apparatus comprising a removable coke-oven door and a door machine for removing said door, said door machine having means for successively unlatching said door, withdrawing it in substantially a straight line and swinging it through an angle of substantially 90°, said means comprising a carriage for supporting said door and means for pivotally supporting said carriage on two spaced axes at different distances from said carriage.

4. Coke-oven apparatus comprising a movable carriage having means adapted to unfasten a coke-oven door, means for movably supporting said carriage comprising two links of unequal length that are pivotally connected to said carriage and to fixed supports.

5. Coke-oven apparatus comprising a door machine having a movable carriage provided with mechanism adapted to control the fastenings of a coke-oven door, said carriage having two spaced pivotal connections for movement about two axes at radii of different lengths whereby said mechanism is caused to traverse a curved path upon movement of said carriage.

6. Coke-oven apparatus comprising a door machine for the coke side of a coke-oven battery, said door machine having a movable carriage provided with door-supporting mechanism, means comprising two spaced arms of unequal length pivotally connected to said machine and to said carriage for moving said carriage horizontally through a path comprising an approximately straight line and a curve, and means for moving said machine.

7. Coke-oven apparatus comprising a door machine for the coke side of a coke-oven battery, said door machine having a movable carriage provided with door-supporting mechanism, said carriage being mounted on two swinging arms of different lengths pivot-

ally connected thereto, and means for actuating one of said arms to effect the movement of said carriage.

8. Coke-oven apparatus comprising a door machine for the coke side of a coke-oven battery, said door machine having a movable carriage provided with door-supporting mechanism, said carriage extending in alinement with a coke-oven when in door-engaging position, two arms of different lengths having spaced pivotal connection to said carriage and to said machine and means for actuating one of said arms about its pivotal support on said machine.

15 9. Coke-oven apparatus comprising a door machine having a movable carriage carried by two horizontal arms of different lengths that are pivotally connected to said carriage and to said machine for horizontal movement and a power device connected to one of said arms, the pivotal axes being so related that upon movement of said one arm, said carriage is moved through an angle of approximately 90°.

25 10. Coke-oven apparatus comprising a door machine for the coke side of a coke-oven battery and having a main body portion mounted for movement along a coke-oven battery, a movable carriage and arms pivotally supporting said carriage and extending beyond one end of said main body portion, said carriage extending transversely of said machine when in door-engaging position and said arms being of such unequal lengths that 35 when said carriage moves away from said oven it assumes a position at right angles to its door-engaging position.

11. In a door-handling machine for coke ovens or the like, a carriage adapted to be positioned opposite the front wall of an oven, a door carrier on said carriage comprising means for grasping a door in its closed position, a vertical pivot support for said carrier, means for swinging said support about a 45 vertical axis spaced therefrom and fixed with respect to the carriage, a horizontally swinging link with its ends connected to said carrier and to said carriage respectively, said parts being so positioned and proportioned 50 that the movement of the carrier from closed door position is in substantially a straight line until the door clears the door frame and thereafter causes the carrier to assume a position approximately at right angles to the 55 closed door position.

12. In a door-handling machine for coke ovens or the like, a carriage adapted to be positioned opposite the front wall of an oven, a door carrier on said carriage comprising 60 means for grasping a door in the closed position of the latter, means for supporting and operating said carrier comprising a pair of horizontal links connected to the carriage and the carrier, said links being spaced apart horizontally, and means for applying power to

swing one of said links, said links being positioned and proportioned to cause movement of the carrier from closed door position substantially in a straight line until the door clears the door frame and thereafter in a 70 curved path to a position approximately at right angles to the closed door position.

In testimony whereof, I have hereunto subscribed my name this second (2nd) day of December, 1927.

RAYNARD CHRISTIANSON.
